UNITED STATES PATENT OFFICE

PERCY COX AND FRANK MCPARTLAND, OF JOHNSON CITY, NEW YORK, ASSIGNEES TO
UNITED SHOE MACHINERY CORPORATION, OF PATERSON, NEW JERSEY, A CORPORA-
TION OF NEW JERSEY

FASTENING INSERTING MACHINE

Application filed July 29, 1929. Serial No. 381,808.

This invention relates to fastening inserting machines and is illustrated herein as embodied in a stapling machine provided with welt and shoe feeding and welt guiding mechanism particularly adapted to be used in fastening welts to the uppers of lasted shoes.

It is common practice to provide certain types of McKay and nailed shoes with welts, both for the purpose of rendering the shoes more water-resistant and to simulate the appearance of Goodyear welt shoes. This has ordinarily been done by fastening the welt to the marginal portion of the attaching surface of the outsole before the outsole is attached to the shoe. If the welt has a beaded edge, as storm welts frequently do, any substantial trimming operation performed after the welt has been attached to the shoe is likely to mutilate the edge of the welt. Moreover, it is difficult to position the welt accurately enough, if the operation is performed in this manner, to cause the welt to contact at all points as it should with the shoe upper. To obviate these and other difficulties we have invented the shoe and method of Letters Patent of the United States No. 1,687,267, granted October 9, 1928. In the manufacture of shoes in accordance with the method of said Letters Patent the welt is fastened to the overlasted portion of the shoe upper before the outsole is attached to the shoe.

It is an object of the present invention to provide a fastening inserting machine particularly adapted to be used as an aid in carrying out the above method. As illustrated herein, the invention is embodied in a staple inserting machine, which may be of the well-known type disclosed in Letters Patent of the United States No. 1,016,930, granted February 13, 1912, on an application of William H. Borden, provided with two power-operated feed rolls, one engaging the shoe upper adjacent to the shoe bottom and the other engaging the surface of the welt opposite the overlasted portion of the shoe upper, the two rolls serving to feed the shoe and welt past the fastening inserting means. Preferably the machine is provided with a welt guide which serves to conduct the strip of welting to the fastening inserting position. As herein illus-

trated, each of the feed rolls is provided with a beveled gear, the two gears intermeshing and one of the gears being mounted on an intermittently rotated shaft so that the two rolls are given a step-by-step feeding movement.

With the above and other objects and features in view the invention will now be described as illustrated in the accompanying drawings and pointed out in the claims.

In the drawings:

Fig. 1 is a front view of a portion of the head of a staple inserting machine provided with welt and shoe feeding mechanism and with a welt guide in accordance with the present invention;

Fig. 2 is a front view illustrating the manner in which a shoe is presented to the machine and the manner in which the strip of welting is attached to the shoe;

Fig. 3 is a perspective view of the power-operated mechanism for operating the feed rolls step-by-step; and

Fig. 4 is a side elevation of the feed rolls and associated parts of the machine.

The illustrated machine, like the machine of said Borden patent, is provided with a nozzle 10 having a throat opening 12 through which reciprocates a driver 14 carried by the reciprocating bar 16 (Figs. 1 and 2). A wire 18 from which staples 20 are formed is fed by a pair of intermittently-rotated feed rolls 22, 24 through a wire guide 26 past the knife 28 to present it to the inside former 30 and the outside formers 32. After a length of wire has been severed by the knife 28 the outside formers are moved downwardly by the counterclockwise movement of a rock arm 34 (Fig. 1) to which they are connected, thereby forming a staple. After this the inside former 30 is withdrawn by mechanism provided for that purpose and the driver 14 descends forcing the staple through the throat opening of the nozzle 10 into a work piece which is presented to the nozzle.

As illustrated in Figs. 2, 3 and 4, the work piece comprises a shoe 36 to which is to be stapled a welt 38 guided to fastening inserting position by a welt guide 40 carried by a

bracket 42 secured to the column 44 of the machine.

The bracket 42 also serves to carry a pair of feed rolls 46, 48 arranged to engage the welt 38 and the upper of the shoe 36, as best shown in Fig. 4. The driver 10 is movable in a plane coincident with the common plane of the axis of said rolls 46, 48, thereby feeding the shoe and the welt past the nozzle 10 of the machine, as indicated in Fig. 2. Preferably the feed roll 46, which engages the surface of the welt opposite the overlasted portion of the shoe upper, is roughened, as illustrated in Fig. 3, to make this feeding action more effective, while the surface of the feed roll 48 is smooth to avoid injuring the shoe upper. Journaled in the bracket 42 is a horizontal shaft 50 which carries at its forward end the feed roll 46. A bevel gear 52 is secured to the feed roll 46 and meshes with a bevel gear 54 secured to the feed roll 48 so that rotation of the shaft 50 serves positively to drive both feed rolls. The shaft 50 is power-operated by connections which will now be described.

Fast upon the main shaft 56 of the machine (Fig. 1) is a cam member provided with a cam track 58 in which is located a cam roll 60 carried by a lever 62 fulcrumed at 64. Pivoted at 66 to the outer end of the lever is a link 68 the other end of which is attached to the upper end of a rack bar 70 mounted for approximately vertical sliding movement in a slideway 72 carried by the bracket 42. Loose upon the end of the shaft 50 is a pinion 74 meshing with the rack bar 70 and, accordingly, rocked first one way and then the other as the lever 62 is oscillated by the rotation of the cam shaft 56. Secured to the pinion 74 is an arm 76 to which is pivoted a spring held pawl 78 co-operating with a ratchet 80 fast on the shaft 50. Thus it will be seen that the shaft 50 is moved intermittently or step-by-step in a clockwise direction, as viewed in the various figures of the drawings, thus rotating the feed roll 46 in the same manner and, by reason of the intermeshing relation of the bevel gears 52 and 54, rotating the feed roll 48 synchronously with the feed roll 46 in a direction to feed the shoe to the left, as viewed in Fig. 2.

In the operation of the machine the end of the welting 38 is passed beneath the nozzle 10 of the machine and the shoe is held by the operator with the upper and the edge of the welt in engagement with the periphery of the feed roll 48 and in position to press the welt 38 against the periphery of the feed roll 46. Then the machine is started and a staple is formed and inserted through the throat opening 12 of the nozzle 10, securing the end of the welt 38 to the overlasted portion of the shoe upper. The staple, as illustrated, passes through the insole 81 of the

shoe and is clenched against the metal bottom plate 80 of the last 82 on which the shoe is mounted. After the staples have been inserted the feed rolls are rotated sufficiently to feed the welt and the shoe a short distance to the left after which they come to rest and another staple is inserted. This operation is repeated progressively along the side of the shoe, around the toe and back along the other side. The welt may be attached, as preferred, either merely from the heel breast line to the toe of the shoe and back to the heel breast line or about the complete periphery of the shoe including the heel seat.

Having thus described our invention what we claim as new and desire to secure by Letters Patent of the United States is:

1. A fastening inserting machine having fastening inserting instrumentalities, and two power driven feed rolls arranged to engage a shoe and a strip of welting presented to the fastening inserting instrumentalities and to feed the shoe and the welting therepast, the periphery of one of the feed rolls being arranged to engage the shoe upper adjacent to the shoe bottom and the other feed roll being arranged to engage a portion of the welt as it is attached to the shoe.

2. A machine for fastening welts to the uppers of lasted shoes having, in combination, fastening inserting means, and two power-operated feed rolls, one engaging the shoe upper adjacent to the shoe bottom and the other engaging the surface of the welt opposite the overlasted portion of the shoe upper, whereby the two rolls feed the welt and the shoe past the fastening inserting means.

3. A machine for fastening welts to the uppers of lasted shoes having, in combination, fastening inserting means, a welt guide arranged to guide welting to the fastening inserting means, and two power-operated feed rolls, one engaging the shoe upper adjacent to the shoe bottom and the other engaging the surface of the welt opposite the overlasted portion of the shoe upper, whereby the two rolls feed the welt and the shoe past the fastening inserting means.

4. A machine for stapling welts to the uppers of lasted shoes having, in combination, staple inserting means and two power-operated feed rolls, the periphery of one engaging the shoe upper adjacent to the shoe bottom and the outer edge of the welt and the other engaging the upper surface of the welt adjacent to the staple inserting means to feed the shoe and the welt past the staple inserting means.

5. A machine for stapling welts to the uppers of lasted shoes having, in combination, staple inserting means, a welt guide arranged to guide welting to the staple inserting means, and two power-operated feed rolls, one en-

gaging the shoe upper adjacent to the shoe bottom and the other engaging the surface of the welt opposite the over-lasted portion of the shoe upper, whereby the two rolls feed the welt and the shoe past the staple inserting means.

6. A fastening inserting machine having fastening inserting instrumentalities, and two power driven feed rolls arranged to engage a shoe and adjacent surfaces of a strip of welting presented to the fastening inserting instrumentalities and to feed the shoe and the strip of welting therepast, one of the feed rolls being rotated about a substantially vertical axis and engaging the shoe upper adjacent to the shoe bottom and one surface of the strip of welting and the other feed roll being rotated about a substantially horizontal axis and engaging another surface of the welting.

7. A welt attaching machine having fastening inserting instrumentalities, and power-operated intermittently-driven feed rolls arranged to engage a shoe presented to the fastening inserting instrumentalities and to feed the shoe therepast, one of the feed rolls being arranged to engage the shoe upper adjacent to the shoe bottom and the other feed roll being arranged to engage a strip of welting as it is attached to the shoe bottom.

8. A machine for use in the manufacture of shoes having, in combination, staple forming and inserting instrumentalities and a pair of feed rolls rotatable about axes arranged substantially at right angles to each other, said staple inserting instrumentality moving in the plane of the axes of said rolls, one of the feed rolls being arranged to engage the upper of a shoe presented to the staple inserting means adjacent to the bottom of the shoe and the other feed roll engaging an element of the shoe bottom, a pair of intermeshing bevel gears, one of the gears being secured to each of the feed rolls, and means for intermittently rotating the bevel gears to feed the shoe past the staple inserting means.

9. A machine for use in the manufacture of shoes having, in combination, staple forming and inserting instrumentalities and a pair of feed rolls rotatable about axes arranged substantially at right angles to each other, said staple inserting instrumentality moving in the plane of the axes of said rolls, one of the feed rolls being arranged to engage the upper of a shoe presented to the staple inserting means adjacent to the bottom of the shoe and the other feed roll engaging an element of the shoe bottom, a pair of intermeshing bevel gears, one of the gears being secured to each of the feed rolls, and pawl and ratchet mechanism arranged to rotate the bevel gears intermittently to feed the shoe past the staple inserting means.

10. A machine for use in the manufacture

of shoes having, in combination, fastening inserting means, a feed roll arranged to engage a bottom element of a shoe presented to the fastening inserting means, a shaft on which the feed roll is mounted, pawl and ratchet mechanism for rotating the shaft and feed roll intermittently, a second feed roll mounted for rotation about an axis substantially at right angles to the axis of the first feed roll and adjacent to the bottom of the shoe, said inserting means moving in a plane coincident with the common plane of the axes of said rolls, and a pair of intermeshing bevel gears, one of which is secured to each of the feed rolls whereby the second feed roll is rotated intermittently in synchronism with the first.

11. A machine for use in the manufacture of shoes having, in combination, staple forming and inserting means, a feed roll arranged to engage a bottom element of a shoe presented to the staple inserting means, a shaft on which the feed roll is mounted, pawl and ratchet mechanism for rotating said shaft and feed roll step-by-step, a second feed roll mounted for rotation about an axis substantially at right angles to the axis of the first feed roll and adjacent to the bottom of the shoe, said inserting means moving in a plane coincident with the common plane of the axes of said rolls, and a pair of intermeshing bevel gears, one of which is secured to each of the feed rolls whereby the second feed roll is rotated step-by-step in synchronism with the first.

12. A welt attaching machine having, in combination, fastening inserting means, a welt guide constructed and arranged to guide welting to the vicinity of the fastening inserting means, a feed roll arranged to engage the welting as it is attached to the bottom of a shoe presented to the fastening inserting means, a shaft on which the feed roll is mounted, pawl and ratchet mechanism for rotating said shaft step-by-step, a second feed roll mounted for rotation about an axis at right angles to the axis of the first feed roll and adjacent to the bottom of the shoe, and a pair of intermeshing bevel gears, one of which is secured to each of the feed rolls, whereby the second feed roll is rotated step-by-step in synchronism with the first.

In testimony whereof we have signed our names to this specification.

PERCY COX.
